Patented May 28, 1968

211,185

COMBINED HOLDER AND CHARGING UNIT FOR ELECTRIC KNIFE OR THE LIKE

Austin E. Cox, Medina, Ohio, assignor to Dominion
Electric Corporation, a corporation of Ohio

Filed Dec. 19, 1966, Ser. No. 5,100

Term of patent 14 years

(Cl. D26—15)

Fig. 1

Fig. 2

Fig. 3

Fig. 4

Fig. 5

Fig. 6

Fig. 7

FIGURE 1 is a front elevational view of a combined holder and charging unit for electric knife or the like embodying my design;

FIGURE 2 is a right hand end view of the same;
FIGURE 3 is a rear elevational view of the same;
FIGURE 4 is a left hand end view of the same;
FIGURE 5 is a top plan view of the same;
FIGURE 6 is a bottom view of the same; and
FIGURE 7 is a perspective view of the same.

I claim:

The ornamental design for a combined holder and

charging unit for electric knife or the like, substantially as shown.
